UNITED STATES PATENT OFFICE.

CHARLES ED. HAVILAND, OF LIMOGES, FRANCE.

DESIGN FOR A PLATE, &c.

SPECIFICATION forming part of Design No. 20,630, dated March 24, 1891.

Application filed February 24, 1891. Serial No. 382,635. Term of patent 14 years.

To all whom it may concern:

Be it known that I, CHARLES EDWARD HAVILAND, a citizen of the United States, residing at the city of Limoges, in the Republic of France, have invented and produced a new and original Design for a Plate or other Article, of which the following is a specification, reference being had to the accompanying drawings, forming part thereof.

10 Figure 1 is a top plan view of a plate, showing my design; and Fig. 2 is a vertical section of same on the dotted line 2 2 of Fig. 1.

The leading feature of my design consists of the conventionalized foliate scrolls lettered 15 in the drawings A, B, C, and D, displayed at

regular intervals around the rim of the plate or other article. The scrolls A, B, and C are in relief, while the scrolls D are *in intaglio* and extend in a direction opposite to that of the line of the scrolls B C, as shown. 20

What I claim is—

The design for a plate or other article, substantially as shown and described.

Signed at the city of Limoges, in the Republic of France, this 10th day of February, 25 1891.

CHARLES ED. HAVILAND.
